CLAIM

The ornamental design for a camera, as shown and described.

DESCRIPTION

This application is related to U.S. Design application Ser. No. 29/719,014, U.S. Design application Ser. No. 29/719,015, and U.S. Design application Ser. No. 29/719,017, all of which are concurrently filed herewith, and the disclosures all of which are incorporated herein by reference.

FIG. 1 is a front and right side perspective view of a camera showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict portions of the camera in which the design is embodied that form no part of the claimed design.

1 Claim, 4 Drawing Sheets
